UNITED STATES PATENT OFFICE.

CHARLES E. RUESCH, OF WEST HOBOKEN, NEW JERSEY, ASSIGNOR OF ONE-HALF TO
EMIL PULVER, OF WEST HOBOKEN, NEW JERSEY.

WORKHOLDER FOR EMBROIDERING MACHINES.

Application filed December 23, 1921. Serial No. 524,359.

To all whom it may concern:

Be it known that I, CHARLES E. RUESCH, a citizen of Switzerland, and resident of West Hoboken, in the county of Hudson and 5 State of New Jersey, have invented certain new and useful Improvements in Work-holders for Embroidering Machines, of which the following is a specification.

In the use of embroidering machines in 10 which a large number of pieces of work or repeats are simultaneously embroidered by the action of the needles and their adjuncts, it has been found that the work-holders or spanners are deficient in several respects, 15 one deficiency being that the opening in the holder or frame across which the work is stretched or spanned is so restricted in area as to prevent the embroidering of a relatively large sized design, while the work is 20 held in the one position, thereby necessitating the intermittent removal of the work from the holder when a portion of the design has been done, and the replacement of 25 the work in the holder, in a shifted or changed position, in order to continue with another portion of the design, and so on until the entire design is completely 30 embroidered, in the desired place on the work. This restriction in the field of embroidering 35 on the work and the necessary stopping of the machine to shift the work in the holder in order to continue the design, not only entails a loss of time in the operation, but also results in great inaccuracy in the work 40 and consequent defective reproductions of the design, as it is practically impossible to re-set the work in the holder in true or correct position with respect to the needle, so as to be able to start in the right place 45 on the design, and this causes gaps or distortions in the design and to that extent spoils the finished piece of work. Another 50 drawback to work holders as heretofore used in large gangs or repeats, has been that the 55 work when stretched or spanned over the work-opening in the holder or frame, was not held securely at all points or sides surrounding said opening, and in some cases the work has merely been held or gripped along opposite points leaving the work material free or unsecured at the other two opposite sides. Still another drawback to the known forms 60 of work-holders used in sets of considerable number or repeats, has been that the work-opening was of such shape or configuration

as to prevent the same from being brought close to each other, with the result that much space has been demanded thereby, so that but comparatively few repeats could be done in one machine. By my present improvements, I seek to overcome these as well as other drawbacks to the old forms of work-holders, and to these ends my invention consists in the various novel and peculiar constructions and arrangements of the different parts of the work holding means, all as hereinafter fully set forth and then pointed out in the claims.

I have illustrated a type of my invention in the accompanying drawings, wherein;

Fig. 1, is a view in elevation of a set of work-holders embodying my invention, there being four in number and with a piece of work being shown as spanned across the work-opening of three of the holders. The 75 set is composed of five plates with the end ones shown as partly broken away.

Fig. 2, is a similar view of a set of the holders, but with the work removed and the holders spaced wider apart than in Fig. 1, 80 so as to enlarge or expand the work-openings thereof.

Fig. 3, is an enlarged elevational view of a single work-holder composed of two adjacent plates one of which is partly broken 85 away and its support shown in part, the work being shown as stretched across the work-opening and the embroidered design as completed on the work.

Figs. 4, 5, 6 and 7, are sectional views 90 of the work-holder comprising two adjacent adjustable plates for expanding the work-opening, the planes of the sections of said Figures being indicated by lines 4—4, 5—5, 6—6 and 7—7, respectively, in Fig. 3.

Fig. 8 is a view of a modified form of the work-holder, shown as formed of one member or plate having a non-expansile work-opening.

Referring to the drawings, in which like 100 numerals of reference designate like parts throughout, 1, 1, are suitably spaced parallel supporting-members upon which are mounted a series of my improved work holders or spanners 2, 2, which are so constructed and 105 arranged as to provide a peculiar and novel form of work-opening 3, some of the important features of which are the right-angled part formed by the sides or edge portions 4 and 5, which make an angle of ninety 110

degrees with each other and form an apex at such place and the expansibility of the work-opening, whereby it may be enlarged or contracted. What may be termed the 5 third side or edge 6, of this opening 3, is on the order of an hypotenuse of the somewhat triangular figure of which edges 4 and 5, form the other two sides. This side 6 lying opposite the right-angle, is shown as 10 bending or curving inwardly towards said angle, as at 7, and forming a reentrant bend at such place; and then curving outwardly near each end, as at 8, and U-shaped in 15 form, thence continuing straight at 9, to each end; and which straight lines 9, may be met by the sides 4 and 5, as shown in Figs. 1 and 3, or may be spaced away therefrom, but intersected thereby when prolonged, as shown in Fig. 2, wherein the work-opening 3, is 20 shown as expanded and made larger than in the other figures. While as already suggested, the side 6, may be made to form a true hypotenuse of a triangle of which the sides 4 and 5, form the other two sides, and 25 in which case the side 6, would be straight, I prefer to form this third side 6, with a reentrant bend or angle 7, to permit of the repeats or groups being brought as close together as practicable and thereby economize 30 space in the embroidering machine and enable the user to assemble a greater number of repeats or pieces of work in a given space in the length of the machine, than otherwise possible, and this is one of the important 35 advantages of my improvements. This feature of the invention will be made clear by reference to Fig. 1, wherein three pieces of work 10, are shown as placed in three of the holders and stretched across the openings 40 3, thereof. By virtue of having the side 6, of the opening formed with a reentrant part 7, which lies well in the right-angle formed by the sides 4 and 5, the pieces of work can be brought closer to each other than if the 45 side 6, of the work-opening were a straight line like a true hypotenuse of a triangle, though my invention covers this latter form and the work is given an extended and firm support close up to the design that is being 50 embroidered.

In the construction herein shown in Figs. 1 to 7, the holder plates or frames 2, are each shaped alike, and the shape is on the order of a V, with the inner edges thereof 55 formed by the right-angled lines 4 and 5, and the outer edges formed U-shaped by the curved or bending portions 7 and 8, 8, with the straight ends 9, 9, the extreme ends of the V figure being rather broad as at 11. 60 As this line 6, forms the outer edges of the V shape, and the right-angled lines 4 and 5, form the inner edges thereof, the angle or center part of the figure is relatively very narrow, so that when two of said frames or 65 plates are brought together in the same

plane with the apices of the right-angles pointing in the same direction, or the V forms nesting in each other, there is provided the peculiar form of work-opening 3, which is very long when measured on the 70 lines 4 and 5, and is comparatively wide at any point across from said lines. The opening 3, accordingly furnishes a substantially V-shaped work-field for the embroidering needle to move over and the area of the same 75 is substantially large and is so disposed as to enable the user to embroider large corner-designs running a considerable distance along the sides 4 and 5, and of a substantial width, without having to remove the work 80 when partly completed and changing its position in the holder to continue the design and complete the same.

When the adjacent edges of a pair of the 85 adjustable frames 2, come together, as at 12, in Figs. 1 and 3, the work-opening is closed at all points of its outline and the opening is then contracted to its smallest size. The frames or plates 2, are however detachably 90 and adjustably mounted on the supports 1, 1, by means of pins or screws 13, 13, passing through holes 14, 14, in the respective ends of the frames, and this permits of the frames being detached and adjusted relatively to each other along the 95 length of the supports in the plane of the frames, so that the frames may be spaced apart from each other, instead of being in contact, and this serves to expand the size 100 of the work-opening 3, as shown in Fig. 2, and thereby greatly increase the width of 105 each branch of the V-form over which the work is spanned. This expansibility of the work-opening formed by two of the adjacent frames or plates is an important feature of my invention.

The piece of work 10, such for example as an ordinary pocket handkerchief, is stretched over the work-opening 3, and held taut in such position during the embroidering operation, by means of a centering pin 15, at the apex of the right-angle formed by the sides 4 and 5, of the opening, one corner of the piece of work being first pushed over this pin to properly position and center the 110 piece of material. Then the two adjacent edges of this corner are laid along the margins of the two edges 4 and 5, over the clamping-grooves 16, and 17, which run along said margins respectively. These 115 grooves 16, and 17, receive clamping-bars 18 and 19, respectively, which are forced down on the work and clamp it in said grooves to hold it taut. These bars are provided at their outer ends with pintles or lugs 120 20 and 21, respectively, which are adapted to turn in eyes or sockets 22 and 23, respectively, which are located on the upper face 125 of the frame 2. This permits of the clamping-bars being swung vertically on their 130

bearings, so that when the work-piece 10, is placed in position with the bars raised, as shown in dotted lines in Fig. 6, the bars may be lowered onto the piece and then forced 5 down into the groove into which the bar fits, and thereby securely clamp and hold the piece in place. On the frame 2, near the outer ends of the clamping-bars, are arranged turn-pieces or buttons, 24 and 25, 10 which may be turned to engage the upper side of the respective bars 18 and 19, and thereby serve to lock them in clamping-position during the operation of the machine. The hinged ends of the clamping-bars 18 and 19, are rounded, as at 26, Fig. 7, to avoid a sharp place or corner which would tend to cut the goods when put in the holder.

A clamping-groove 27, is formed on the 20 frame 2, along the margin of the side 6, of the work-opening, following the curved U-shaped outlines of the side, and a resilient strip of metal 28, is fitted to this groove so as to snap therein, so that when the piece 25 of work has been clamped by the two bars 18 and 19, and is drawn taut across the work-opening 3, without wrinkles, it is pulled over the sinuous clamping-groove 27, and the clamping-strip 28, is thereupon forced down on the piece which is pushed into the groove by the strip and firmly held therein, the resiliency of the metal strip serving to retain itself in the groove. Thus 30 the curves in the sinuous clamping-groove 27, make the engaging resilient strip self-retaining in the groove, and this is one advantage in having this groove so formed, instead of being straight. It will also be noted that the outer ends of the clamping-strip 28, curve to conform to the curvature 35 8, 8, at each end of the edge 6, of the work-opening 3, and that the strip 28 does not terminate abruptly or short of the end of the work-opening, for in the latter case, the 40 ends of this strip would be apt to cut or lacerate the material of the work, so that I thus avoid all liability of perforating or injuring the material, when the same is placed in the holder and clamped in place under tension, and obtain perfect spanning of the 45 piece of work in the holder.

The pieces of work 10, which I show herein, after being spanned and clamped in operative position across their respective work openings, as hereinabove described, have their free ends rolled up, as shown in Figs. 1, 3, 4 and 5, so as to bring the un-spanned material into a snug bunch to get it out of the way as much as possible. Owing to the 50 form of the work-opening and the arrangement of the clamping-strip 28, the rolled piece takes the form of a V, and is very compact, occupying only the narrow space lying between the curved side 6, of its own holder 55 and the right-angled sides 4 and 5, of the

next succeeding holder, and in this out of the way position, the roll is clamped by a small spring-clamp 29, at about the center of the roll, while the respective ends of the roll are drawn under spring-fingers 30 and 31, respectively, which are arranged on the frames or plates 2, near the ends thereof. In addition to the spring-clamp 29, other clamps may be used for the roll of material to keep it well in place on the shelf-like 70 space lying between the two opposite edges of a plate, and having a V shaped area.

As above stated the work-opening 3, may be enlarged or contracted by the proximity 80 of two adjacent plates 2, 2, to each other, and the plates are made adjustable in their own planes for this purpose. In Figs. 1 and 3, the plates are shown as in edge contact so that the opening 3, is of the minimum size 85 for these particular plates, while in Fig. 2, the plates are spaced quite a distance apart, thereby enlarging the work-opening. This adjustment of the size of the work-opening is provided for, in order to accommodate 90 different sizes of designs or patterns, and it gives the holder a wide range and capacity in this respect. It will also be noted that the peculiar form or contour of the work-opening results from the peculiar shape of the V form of plate, the V having its arms 95 of narrower width near the point than at the outer ends, the cross-section gradually increasing from the point outwardly.

In the modification shown in Fig. 8, a 100 single plate 2^a, is employed in place of two separate ones, and this plate is formed with a non-expansible work-opening 3^a, the clamping-bars and grooves and the detachable spring clamping strip being the same as hereinbefore described. This form possesses 105 all of the advantages of the other, except that of having the capacity to vary the size of the work-opening.

The frames or plates are mounted in any suitable manner and in some construction of machines they are arranged in the same vertical plane in a horizontal row, for co-operating with the needles in the usual way, while in other cases the plates may be disposed horizontally.

The plates or frames 2, of the holder, 110 may be made of any suitable material, such for example as brass or bronze, and may be cast or rolled and made from any kind of sheet-metal suitable for the purpose, the character of the plate lending itself to stamping or die-work in forming it from sheet-metal. The size of the plates may be made to suit the particular class of work 115 with which it is to be used and the mounting of the plates may be varied to fit the special embroidery machine, that is equipped with the plates and which employ a large number of similarly operated needles 120 in gangs or sets, in a manner well known 125 130

and which it is not necessary to illustrate herein. As indicated herein, the plates are made as a unit with the edge grooves for the different clamping devices and the latter are mounted in place on the plates as shown so that each is complete in itself.

From the foregoing description, it will now be readily understood that by reason of the peculiar construction and arrangement 10 of the work-opening of my improved holders, I am able to place in a given length of space, more repeats or groups of pieces of work, than with the heretofore known constructions of holders, for it will be seen that 15 the V shaped openings permit of the same being brought closer together than would be the case were the openings of a different shape. The V forms are arranged with their points in the same direction and with a 20 nesting effect, thereby increasing the production or repeats on a given size of machine. I am also enabled to insure greater accuracy in the work of the designs when finished and the spanning of the cloth or work is perfect. 25 The design shown at 32, in Fig. 3, may be completed throughout by the use of my improved holder, without shifting the position of the work in the holder, as the peculiar shape of the work opening permits the 30 needle to operate over the entire space occupied by the design, whereas with the use of the holders now in use, having a straight or rectangular work-path, only a part of certain corner-designs can be done at a 35 time, the work being removed and shifted in the holder to complete the other half, with the inevitable result of making defective pieces of work, as the lines or places cannot be matched in renewing the 40 embroidery after the work has been shifted in the holder. It will thus be seen that my peculiar form of elongated work-opening which bends or turns in its course, has important advantages over the prior forms of 45 such devices, and, as each of the co-operating holder frames is adjustable, the respective work-openings thereof are thereby made expansible to accommodate designs of different sizes. It will also be noted that 50 my improved work-holder frame or member is made in a single-piece and each one carries fabric or work clamping devices disposed along each of its two opposite edges, which edges form part, respectively, of adjacent work-openings. The structure is 55 thus a unitary one that is self-contained, in that it is of one-piece and itself carries the fabric clamping devices.

I wish to be understood as not limiting my 60 invention to the particular constructions and arrangements herein set forth, as it is evident that various modifications may be made in different parts of the same, without, however, departing from the spirit of 65 the invention.

Having thus described my invention, what I claim and desire to secure by Letters Patent, is:

1. In an embroidering machine, a work-holder having a work-opening across which the material is placed with one side of said opening having a V-shaped formation and the opposite side thereof formed substantially U-shaped with the apex of the latter projecting towards and in line with the apex 75 of the former, clamping-grooves extending along the edges of said V-shape, clamping-bars hinged near the outer ends of said V-shape and closing towards the apex thereof and means for holding said clamping-bars 80 in closed positions, and a clamping member arranged along the edge of said U-shape for securing the work material at said point.

2. In an embroidering machine, a series of work-holders provided with work-openings 85 and each holder comprising a pair of frames each of which has its outer edge formed U-shaped and its inner edge formed V-shaped with the apices thereof projecting in the same line axially with each other, means for clamping the work material along each of said edges, said pair of frames being mounted adjacent each other, so that the intermediate space between the inner edge of one frame and the adjacent outer edge of the 90 other forms a work-opening.

3. In an embroidering machine, a work-holder consisting in one piece members adjustable relatively to each other, the said members being constructed to be arranged adjacent to each other and each pair providing a work-opening therebetween, each of said members being provided upon opposite edges with work clamping means carried thereby and engaging the adjacent ends or 105 parts of two separate pieces of work, said work-clamping means being movable with said adjustable members.

4. In an embroidering machine, a work-holder having a work-opening across which the material is stretched and constructed and arranged to permit the embroidering to be done in the corner of the work and for a considerable distance along each of the meeting edges at said corner, said work-holder comprising a pair of separable co-operating members one of which has its inner edge formed V-shaped and the other having its outer edge formed with a salient projecting into and reentrant with respect to said V-shaped edge, said members being relatively adjustable to enlarge or decrease said work-opening in order to extend or contract the area at the corner of the work where the embroidering is done, the said reentrant part of said member giving an extended and firm support to said work at said corner and making the holder more compact and causing it to occupy less space.

5. An embroidering-machine work-holder

- having an opening across which the work is stretched, said work opening having a part of its edge formed with an angle, means for securing said work along the sides forming 5 the angle, the said opening having an edge portion lying opposite the said angle and projecting into said angle so as to be reentrant therewith, said opposite side being provided with a sinuous clamping groove and a 10 detached clamping strip of resilient material adapted to engage said groove and retain itself and the work therein by the resiliency of said strip.
6. An embroidering-machine work-holder 15 comprising separate co-operating plates having opposing edges cut-away with one edge reentrant with respect to the other to form therebetween a substantially V shaped work-opening and so that three of said 20 plates cooperate to provide two of said work-openings, and means for securing the work in spanned position across said opening.
7. An embroidering-machine work-holder including sets of co-operating plates having 25 opposing angular edges forming a work-opening and relatively adjustable to vary the work-opening between them, and means for clamping the work in spanned position across the opening between the plates.
8. An embroidering-machine work-holder 30 member having the edge thereof at one side formed substantially V-shaped and the edge thereof at the opposite side formed with a salient and constructed and arranged so that 35 when a set of said members is placed side by side in cooperating positions an elongated work-opening is provided between opposing edges of adjacent members with said salient part reentrant with respect to said V-shaped 40 edge and three of said members may cooperate to provide two of said work-openings.
9. An embroidering-machine work-holder
- plate shaped substantially like a V and gradually increasing in width from the apex 45 toward each end and having clamping means mounted on its opposite edges and carried thereby.
10. Embroidering-machine work-holders comprising a set of V-shaped plates adapted 50 to be placed in cooperating positions side by side with the apices of said V-shapes disposed in the same direction in nesting arrangement so as to provide work-opening between adjacent plates, and relatively adjustable to vary the size of the work-opening and work-clamping means located on the opposing edges of adjacent plates, whereby three of said plates may cooperate 55 to provide two of said work-openings.
11. Embroidering-machine work-holders comprising a series of relatively adjustable plates substantially V shaped and so constructed as to permit of the plates being placed in side-by-side relation so that two 60 adjacent plates form between them a work-opening having an edge part substantially right-angled and another edge part opposite said angle, and releasable clamping devices located along said right-angled part and 65 said opposite edge.
12. An embroidering-machine work-holder comprising substantially V shaped frames constructed and arranged so as to provide a work-opening between adjacent 70 frames, clamping means arranged along the opposite edges of each frame with a shelf-like space between the same for receiving the rolled surplus of cloth or material and means carried by said frames for securing 75 said rolled material in place.

Signed at New York, in the county of New York and State of New York, this day of December 21, A. D. 1921.

CHARLES E. RUESCH.
